UNITED STATES PATENT OFFICE.

MORRIS N. DRUCKER, OF CINCINNATI, OHIO.

DESIGN FOR A CORNER-SHIELD FOR TRUNKS.

SPECIFICATION forming part of Design No. 33,743, dated December 18, 1900.

Application filed October 31, 1900. Serial No. 35,053. Term of patent 7 years.

To all whom it may concern:

Be it known that I, MORRIS N. DRUCKER, a citizen of the United States of America, and a resident of Cincinnati, in the county of Hamilton and State of Ohio, have invented and produced a certain new and original Design for a Corner-Shield for Trunks, of which the following is a specification.

Figure 1 is a top view of a corner-shield embodying my invention. Fig. 2 is a side view of the same.

The principal feature of my corner-shield is a semispherical head, around the base of which is a series of circular bands.

The corner-shield consists of three plates 15 *a*, which lie in planes which converge toward a point like the sides of a pyramid, surrounded by a head *a'*, around the base of which are two circular bands *a²* and *a³*.

What I claim is—

The design for a corner-shield for trunks, as herein shown and described.

MORRIS N. DRUCKER.
